(57) **CLAIM**

An ornamental design for a teether ball as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a teether ball in accordance with an embodiment of my new design; FIG. 2 is a rear elevational view of the teether ball illustrated in FIG. 1;

FIG. 3 is a left side elevational view of the teether ball illustrated in FIG. 1;

FIG. 4 is a right side elevational view of the teether ball illustrated in FIG. 1;

FIG. 5 is a top plan view of the teether ball illustrated in FIG. 1;

FIG. 6 is a bottom plan view of the teether ball illustrated in FIG. 1;

FIG. 7 is a perspective view of the teether ball illustrated in FIG. 1;

FIG. 8 is a front elevational view of a teether ball in accordance with another embodiment of my new design that is shown in color;

FIG. 9 is a rear elevational view of the teether ball illustrated in FIG. 8;

FIG. 10 is a left side elevational view of the teether ball illustrated in FIG. 8;

FIG. 11 is a right side elevational view of the teether ball illustrated in FIG. 8;

FIG. 12 is a top plan view of the teether ball illustrated in FIG. 8;

FIG. 13 is a bottom plan view of the teether ball illustrated in FIG. 8; and,

FIG. 14 is a perspective view of the teether ball illustrated in FIG. 8.

The embodiment shown in FIGS. 8 to 14 is identical to the embodiment shown in FIGS. 1 to 7, except that the embodiment

(Continued)

ment shown in FIGS. 8 to 14 is shown in color. The teether ball in accordance with the embodiment shown in FIGS. 8 to 14 has a center portion having a white color, a first pair of rings having a blue color, a second pair of rings having a red color, and a third pair of rings having a yellow color.
